APPARATUS FOR AIR PURIFICATION

John A. Smith, Cincinnati, Ohio, assignor to The United States Electrical Tool Company, Cincinnati, Ohio, a corporation of Ohio

Application June 8, 1931, Serial No. 542,746

7 Claims. (Cl. 183—14)

This invention relates to an apparatus or system for collecting dust and other abrasive particles from the air and for otherwise purifying the air in an operating room, which method and apparatus are particularly applicable to machines such as grinders, finishing, or burnishing machinery, in which machines, abrading or grinding wheels are used, these wheels tending to throw off and fill the surrounding air with metal dust, grit and abrasive substance of all sorts, naturally detrimental to the health and comfort of the workmen.

It is the object of this invention to provide a means or system for drawing off the particle laden air immediately about the grinding devices through the medium of an apparatus efficiently and completely drawing in, through ample air supply inlets, all the particles leaving the parts being ground and the grinding wheels and passing this particle laden air through a water spray for washing the air and thereafter passing the air under pressure through various filters and ultimately returning it to the operating or working room.

By the use of the equipment herein provided, all the grit and dust is carried off and collected through improved intake devices thereby preventing dispersing of the grit and dust within the work room, by means of a unitary apparatus compactly arranged relative to the machine and necessitating no outside connections. Moreover the apparatus treats the air as it is being rid of the abrasive particles, washing, filtering, and returning it in better condition of purification than when it was initially drawn past the grinding wheels into the system, whereby not only the workmen immediately about the machine operating the same, but all those within the entire workroom are benefited by the condition of the discharged air returned for circulation through the operating room.

Other objects and certain advantages will be more fully apparent in a description of the accompanying drawings, in which:

Figure 1 is a rear view of the system applied to a grinding machine, a portion thereof being broken away for illustrating the interior of the filter and air purification unit.

Figure 2 is a sectional view taken on line 2—2, Figure 1, further detailing the air washing device and filter of the system.

Figure 3 is a side view of the system as applied to a grinding machine.

Figure 4 is a front view of one of the intake hoods disposed about a grinding wheel.

Figure 5 is a sectional view of the joint used for sealing the connection between the hood and hopper sections of the intakes.

It is preferable that the body or supporting frame of the machine, to which the system is applied, be hollow for housing the filtering and purifying unit of the system although it will be understood that the system only loses the feature of compactness, relative to the machine, if this is not possible. Likewise it is preferable that the apparatus of the system derive its power from the general power means for the machine.

In the present embodiment and environment the system is shown in its preferred form and arrangement and is incorporated as a part of a grinding machine. The grinding machine, as will be found upon reference to the drawings, includes the major parts related as follows. A hollow frame or base 10 includes a spindle bearing arm 11 projecting upwardly and providing a pair of bearings 12 for the grinding wheel spindle 13 which carries a grinding wheel 9 at each end beyond each of the respective bearings. A motor 14 is mounted on a base 15 secured to the upper surface of the frame 10 toward the rear and centrally thereof. The motor pulley 16 is connected to a pulley 17 on the spindle by means of a belt 18, the spindle being beyond and parallel to the front of the machine for disposing the grinding wheels clear of the machine.

In the present invention, hoods and suction means of improved construction are incorporated in a general purification system for the purposes mentioned heretofore. Each grinding wheel is housed as far as is feasible keeping in mind accessibility to the wheels for efficient work. The improved intake means 19, 19 of this system, having suction connections 20, depend well below the wheels and the intake area is increased well above that obtainable immediately about the wheels by providing that the entire fronts of the intake means are open. These intake means each include a hood section about the grinding wheel and a hopper section below the grinding wheel.

It is recognized that although most of the flying metal dust and abrasive is thrown by centrifugal force into the hood section at the region of each wheel, a portion of it drops or falls the air beneath the wheel. By the present arrangement, this is also drawn into the intake opening of the hopper section in each case as it falls before the downwardly extended intake opening.

Each intake means, as stated, is sectional including a hinged upper section or hood 21 which

can be thrown back from the wheel and a lower supporting section or hopper 22. This lower section or hopper includes a plurality of baffle plates 23 set obliquely at angles varying from the vertical toward horizontal. The inclined arrangement of the baffles is such that they extend toward the suction connection or outlet of the hopper from vertically spaced points along the intake opening beneath the grinding wheel thereby functioning to block the path of particles thrown by centrifugal action off the back of the grinding wheels and diverting all the particles toward the suction connection. It will be observed that the suction intake opening has considerable area, this being possible below the wheels because of the baffles preventing forcible ejection of particles from the periphery of the wheel through the opening, the deflecting baffles aiding the suction means as it pulls the flying abrasive from the region of the wheel.

Each supporting section or hopper is attached to the frame of the machine by means of bracket bars or formed angle iron strips 24 and 25, secured to the back of the hopper section, and the underside of the hopper section respectively. The upper end of the lower section is reinforced or bound by means of an angle iron strip 26 at each side and a U-shaped strap iron piece 27 surrounding the side and rear of the section. The sides or arms of the U-shaped piece are attached to the angle iron pieces and extend well to the rear of the hopper structure disposing the cross bar 28 thereof for supporting the hood when it is thrown back on its hinged rear edge.

The lower side edges of the upper section include locking or sealing connection strips 29. These strips are attached to the inner side of the upper section. They are formed to provide two downwardly disposed channels, the inner 30 (see Figure 5) engaging over the upper edge of the lower section when the hood is in position and the outer 31 having secured therein a felt strip 32 depending therefrom and engaging the particular side of the lower section for sealing the joint at these points, the hinge sealing the sections at the back. The upper section or hood is semicircular and encloses slightly more than half the wheel, the sides thereof being notched as at 33 to clear the spindle and the grinding wheel hubs.

The suction is created by means of a blower fan (not shown) included in a fan casing 34 supported about the motor shaft at the opposite side to the driving pulley thereof. The suction ducts 20 to the respective hoppers are joined at the side of the machine at which the suction means is disposed and are connected to the side of the suction casing by means of a duct 35 of increased size equivalent in cross sectional area to that of the two suction ducts.

These suction ducts may be connected to the hoppers by any suitable sleeve connection and clamping means 36 and the one extending in back of the machine is supported on the machine by means of brackets 37 bolted to sleeves 38 which connect the respective sections of the duct. The duct construction consisting of elbows and straight sections suitably joined is of conventional character and no further description thereof is given.

From the point of the blower the particle laden air is forced under pressure through a duct 39 extending upwardly from the suction casing and thence downwardly in front of the motor into the hollow frame of the machine. The water spray

for washing the air is included within the aforesaid pipe in the downwardly extended section thereof.

The water is supplied from a tank 40 contained within the hollow frame and is pumped through a spray supply pipe 41 by means of a pump 42 bolted to the side of the frame and driven by means of a belt 43 connecting the pump pulley 44 to a pulley 45 on the spindle between one of the grinding wheels and the adjacent spindle bearing. The water pump includes an intake pipe connection 46 entering the water tank below the normal level of the water. The spray supply pipe 41 extends from the pump upwardly and includes a valve 47 for controlling the flow therethrough. This pipe extends out over the frame of the machine and into the side of the duct 39, leading from the blower, by means of appropriate elbows and is extended upwardly centrally of the duct to a point just below a conical baffle 48 having its concave surface disposed downwardly and secured centrally of the pipe by means of radial attaching brackets 49.

The water is forced under pressure into the cone of the baffle and is diverted by means of the conical wall in the form of a conical spray, thereby entirely filling the duct from the point of the baffle to the lower end of the pipe, which lower end is disposed slightly above the normal level of the water. Therefore, the particle laden air forced under pressure past the spray cone passes through the continuous spray of water from the point of the baffle substantially to the level of the water in the tank. The duct 39 extends into the tank through the upper surface thereof and is secured thereto by means of circular flange elements, upper 50 and lower 51, clamped to the sheet metal top of the tank.

A filtering screen box or enclosure 52 entirely surrounds the lower end of the pipe and is supported so as to be partly immersed in the liquid pool. This enclosure is constructed of angle iron providing a general metal framework 53 and screen sides 54, bottom 55 and top 56, and is removably supported on angle iron rails 52^a mounted between and attached to the respective side walls of the water tank. Therefore, the washed air coming out of the bottom of the pipe must pass through the filter screen box into the region of the tank above the water level. It is appreciated that the air discharged from the pipe 39 into the tank is considerably filled with moisture and it would not be feasible, therefore, to discharge the drenched air immediately into the work room from the tank. For this reason the outlet from the tank includes a screen 57, which screen is designed to collect the major portion of the moisture from the air passing through. It is secured in position so as to be readily opened for access to the interior of the tank and is inclined over the pool of water in the tank so that the collected water may drip into the pool.

A plate 58 is hinged to the rear edge 59 of the tank top and depends therefrom. The screen, which includes a metal binding 60, is hinged to the upper edge 61 of the rear wall of the tank which edge is considerably below the rear edge of the top of the tank. The outlet screen 57 has its upper inward edge 62 supported on an angle strip 63, secured to the depending metal plate and is attachable thereto by means of winged nuts 64 which are conveniently detachable to permit swinging of the screen rearwardly and

the plate 58 inwardly for entrance into the water tank.

The back of the machine frame is closed by means of a removable plate 65 having an off-set portion 66 fitting in back of a permanently attached bottom closure plate 67 and adapted to lie against the side edges and upper edge of the frame and secured in this position by pivoted latches 68 engaging in notches 69 of component latch plates 70 secured at right angles thereto and upon the sides of the frame. This removable rear plate 65 is vented for an outlet into the room including for this purpose a series of inclined walls 71 directing the discharge toward the floor of the room, the openings or spaces between the walls providing sufficient aggregate discharge area and being located directly adjacent the screened discharge opening from the tank.

Therefore, it will be observed that the abrasive and particle laden air is drawn off the grinding wheels into the blower and then forced through the spray pipe where it is washed by the water spray, thence passing into the filter screen box within the tank. Thereafter it is discharged through to the upper region of the water tank via the screen sides of the box and from the water tank is discharged through the water collecting screen in the tank outlet and from the hollow machine frame is discharged through the baffled vents in the removable plate at the rear of the frame.

This apparatus is effective for collecting the dust and particles from the air within the tank where they are submerged in water and therefore prevented from being blown or returned into the room, the action of the water spray being to dampen the particles and to positively deposit them in the water pool and the effect of the screen enclosure being to collect any further particles in the air and to prevent undue splashing in the tank. The screened discharge opening for the water tank collects the water from washed air and the baffled discharge deflects the purified air to the floor of the factory room.

Having described my invention, I claim:

1. An air purifying apparatus comprising, hoods adapted to be disposed at the source of emanation of abrasive dust, a blower, intake ducts connecting the blower to said hoods, a discharge duct for said blower for discharging the purified air from the apparatus, a water spray means in said discharge duct, and a filter surrounding the discharge end of said duct.

2. An air purifying apparatus, comprising, hoods for receiving abrasive dust, a blower, intake ducts connecting said blower to said hoods, a discharge duct for the blower discharging the purified air from the apparatus, a water spray device located in said duct, a filter screen enclosure surrounding the lower end of said duct, a tank surrounding said screen enclosure for receiving the water from the spray, and a screened discharge opening for said tank.

3. An air purifying apparatus, comprising, hoods adapted to be disposed about dust creating machinery, means for drawing the dust into said hoods including a blower, an intake duct and a

discharge duct, said discharge duct discharging the air from the apparatus, a spray device located in the discharge duct for washing the air, a supply tank for said spray located within the machine frame, and a filter screen device in said tank, said discharge duct extending into the tank and having its end surrounded by said filter screen device.

4. In an air purifying system adapted to be used on machines creating dust, hoods adapted to be disposed about the machine parts creating dust, a blower adapted to be mounted on top of the machine, an intake duct connecting said blower to said hoods, a discharge duct adapted to extend into the machine, a water spray device located in said discharge duct, a filter screen enclosure surrounding the lower end of said discharge duct, a tank surrounding said screen enclosure for receiving the water from the spray, said discharge duct adapted to be disposed slightly above the water level, and a discharge opening for said tank.

5. An air cleansing apparatus adapted for use on a grinding machine, having a hollow base, intake hoods adapted to be disposed about the grinding wheels, a blower connected to the hoods and adapted to be mounted on the hollow base, a discharge pipe adapted to extend from the blower down into the hollow base of the machine, a water spray device within the discharge pipe, a water tank adapted to be contained within the hollow base, a pump for pumping the water from the tank into the discharge pipe against the spray device, said discharge pipe extending into the tank adjacent the surface of the water contained in the tank, a screen enclosure surrounding the lower end of the pipe and partly submerged in the water, and a screened outlet for the water tank for permitting discharge of the cleansed air therefrom.

6. In an air cleansing system adapted for use on a machine having working parts causing dust and flying abrasive and including a hollow base, an air filtering and washing unit adapted to be contained within said hollow base, a blower means including intake hoods adapted to surround the machine parts causing the dust, said blower connected for discharging into the air filtering and washing unit, and outlet means adapted to be contained in the hollow base for discharge of the purified air back into the room.

7. An apparatus for entraining at the source an emanation of finely divided matter held in air suspension and for delivering a current of purified air; comprising, an intake hood, a blower having its suction conduit connected to the hood, a spraying means located in the discharge conduit of the blower adapted to create a water vapor, a water tank located beneath the end of the discharge conduit, and a filter screen and a deflector disposed about the end of the discharge conduit whereby the finely divided matter is damped and deposited in the pool of water and the washed air is blown across the surface of the water and delivered to the room through the filter and the deflector.

JOHN A. SMITH.
